UNITED STATES PATENT OFFICE.

HAROLD ROEDE, OF WEEHAWKEN, NEW JERSEY.

DESIGN FOR AN ENGAGEMENT-RING.

48,763.

Specification for Design.

Patented Mar. 21, 1916.

Application filed October 19, 1915. Serial No. 56,809. Term of patent 14 years.

To all whom it may concern:

Be it known that I, HAROLD ROEDE, a citizen of the United States, and a resident of Clifton Park, Weehawken, in the county of Hudson and State of New Jersey, have invented a new, original, and ornamental Design for an Engagement-Ring, of which the following is a specification, reference being had to the accompanying drawings, forming part thereof.

Figure 1 is a side elevation of an engagement ring showing my new design; Fig. 2 is an edge view of the ring.

Between the body 10 of the ring and the

stone carrying crown 11 appear representations of two interlinked hearts 12 pierced by an arrow 13. The representation appears in open framework on both sides of the ring, and the representation is flanked by connecting bars 15 extending tangentially from the ring body 10 to the crown 11.

I claim:

The ornamental design for an engagement ring, as shown.

HAROLD ROEDE.
